TOOL BLADE FOR CULINARY TONGS OR THE LIKE

Casimir F. Gruska, Chicago, Ill., assignor to Ekco Products Company, Chicago, Ill., a corporation of Delaware

Filed Oct. 16, 1964, Ser. No. 82,193

Term of patent 14 years

(Cl. D44—4)

Fig. 1

Fig. 2

Fig. 3

FIG. 1 is a front elevational view of a tool blade for culinary tongs or the like showing my new design.

FIG. 2 is a side view thereof.

FIG. 3 is a rear view thereof.

I claim:

The ornamental design for a tool blade for culinary tongs or the like, as shown.
